UNITED STATES PATENT OFFICE.

EDWARD LEWIS, OF NEW YORK, N. Y.

ALARM DEVICE.

Application filed March 17, 1922. Serial No. 544,604.

To all whom it may concern:

Be it known that I, EDWARD LEWIS, citizen of the United States, residing at New York, in the county and State of New York, 5 have invented certain new and useful Improvements in Alarm Devices, of which the following is a specification.

This invention relates to a detonating device for use as a burglar alarm, and the like.

10 An object of the invention is to provide a detonating device which may be quickly and easily fastened in position adjacent a relatively movable element such as a door, a window, or other feature of house construction, and which will be operated by movement of said movable element.

15 A more specific object is to provide a detonating device comprising a body part and a trigger part, to provide means whereby 20 the device may be held in position so that the trigger part, when set, will stand in the path of movement of a house door, or the like, in such manner that when the door is opened the trigger will be thrown to firing 25 position against a suitable cartridge.

Other objects and aims of the invention, 30 more or less specific than those referred to above, will be in part obvious and in part pointed out in the course of the following 35 description of the elements, combinations, arrangements of parts and applications of principles, constituting the invention; and the scope of protection contemplated will be indicated in the appended claims.

35 In the accompanying drawings which are to be taken as a part of this specification, and in which I have shown merely a preferred form of embodiment of the invention:—

40 Figure 1 is a side elevational view of a device constructed in accordance with this invention, a portion thereof being shown in central section for the disclosure of details, and the device being shown in association 45 with a door frame and door, and

Figure 2 is a front elevational view of the structure seen in Fig. 1.

Referring to the drawings for describing in detail the structure which is therein illustrated, the reference character L indicates the door frame, while the reference character G indicates the door. These parts of house structure are shown merely to illustrate a relatively stationary part, as the door frame L, for carrying the detonating device which is indicated generally by the ref-

erence character H, and a relatively movable part, as the door G.

The detonating device H consists of a main body portion 1 and a trigger portion 60 2. The body portion is provided with a retaining thumb screw 3 by which it may be conveniently and securely attached to the part L. The trigger 2 is pivotally mounted, as at 4, between a pair of ears 5 and 6 which 65 project from one end of the body. The heel, or pivot, portion of the trigger is notched to provide two substantially right angularly disposed walls 7 and 8 arranged to receive pressure from a spring pressed 70 plunger 9, the wall 7 being arranged to receive pressure when the trigger is in detonating position, and the wall 8 being arranged to receive pressure when the trigger is in "set" position. The plunger 9 is mounted 75 in a cavity 10 provided for it within the body, and it consists of a head portion 11 and a stem portion 12 which extends backwardly from the head and is received in a seat 13 of the body, said seat providing 80 a shoulder, as 14, at its mouth against which the rear end of the spring 15 abuts, the forward end of the spring being disposed to press against the rear surface of the head. The plunger as thus constructed 85 is mounted to swing freely from one side to the other of the center line of pivot 4 and about a pivot in the seat 13.

When the trigger is in "set" position, as indicated by the dotted lines in Fig. 1, the 90 head 11 has its end pressing against the wall 8 of the trigger, movement of the trigger into "set" position having been limited by engagement of the wall 7 of the trigger against the head 11 and consequent engagement of the head 11 against the upper wall 16 of the cavity.

When the door G is moved open so that it engages and swings the trigger toward detonating position, such movement of the 100 trigger will cause the head of the plunger to be moved downwardly until as it passes the center line of pivot 4 it will suddenly snap to its lower position and exert its full force against the wall 7 for throwing the 105 trigger against the cartridge 17 which is carried in a suitable chamber 18 of the body.

The trigger is provided with an appropriate form of detonating point, as 19, for directly striking the head of the cartridge. 110

If desired a further enlargement of the trigger, as indicated at 20, may be provided

for engaging the body to positively limit movement of the trigger toward detonating position, said enlargement being intended solely for the purpose of preventing injury 5 to the point 19 in the event of operation of the trigger when no cartridge is in position to receive the blow.

It should be mentioned further that this device may be used in various other instances 10 than of giving an alarm against house burglary, for instance, it may be used as a safety alarm in connection with the operation of different kinds of engines, boilers, or other machinery, or as an alarm against the theft 15 of automobiles and the like. When certain parts of such machinery or vehicles move to dangerous and improper limits they may trip the trigger of this device and produce detonation.

20 As various changes could be made in this construction without departing from the invention, it is to be understood that all matter contained in the above description or shown in the accompanying drawings is merely illustrative of one embodiment of the invention but, that the scope of protection contemplated is defined in the following claims.

Having thus described my invention, what I claim as new and desire to secure by 30 Letters Patent is:—

1. An alarm device comprising a body portion and a trigger portion, means whereby the trigger portion is pivotally connected with the body portion to swing between "set" 35 and "detonating" positions, and an operating member exerting a yielding pressure

against said trigger portion adapted to pass dead center for urging the trigger portion to either of its extreme positions, said operating means comprising a plunger spring 40 pressed longitudinally against said trigger portion, and said trigger portion having a part thereof arranged to engage against a side surface portion of the plunger to thereby limit movement of the trigger portion in 45 "set" position.

2. An alarm device comprising a body portion and a trigger portion, means whereby the trigger portion is pivotally connected with the body portion to swing between "set" 50 and "detonating" positions, and an operating member exerting a yielding pressure against said trigger portion adapted to pass dead center for urging the trigger portion to either of its extreme positions, said operating means comprising a plunger spring 55 pressed longitudinally against said trigger portion and adapted to swing laterally into and out of engagement with a portion of said body, and said trigger portion having an extension thereon arranged to engage against a side surface of the plunger to swing the plunger against said body to thereby constitute the plunger as a stop engaged by said trigger extension to limit movement 60 of the trigger into "set" position.

In testimony whereof I affix my signature in the presence of two witnesses.

EDWARD LEWIS.
